UNITED STATES PATENT OFFICE.

THOMAS J. COSTELLO, OF WARREN, OHIO, ASSIGNOR, BY MESNE ASSIGNMENTS, TO COSTELLO ENGINEERING COMPANY, OF PITTSBURGH, PENNSYLVANIA, A CORPORATION OF PENNSYLVANIA.

METHOD OF OPERATING HEATING FURNACES.

Original application filed October 30, 1920. Serial No. 420,593. Patent No. 1,447,588. Divided and application filed May 28, 1921, Serial No. 473,436, Patent No. 1,530,239, dated March 17, 1925. Application for reissue filed June 25, 1926, Serial No. 118,576.

Figure 1 is a longitudinal section illustrating one form of furnace for carrying out my invention;

Figure 2 is a detail view, partly in end elevation and partly in section, showing the positioning of the billets; and

Figure 3 is a sectional plan view; also showing the positioning of the billets in the furnace.

10 My invention has relation to the method of operating heating furnaces, and more particularly to the operation of furnaces for heating sheet and tin plate bars, slabs or billets.

15 One object of the present invention is to utilize the material being heated as a division wall between adjacent heat circulating flues, whereby the opposite sides of the material are directly subjected to the action 20 of the heated products of combustion passing through said flues.

A further object of the invention is to utilize the projections formed on the material during shearing as a separating or 25 spacing means for adjacent billets, bars or slabs.

30 A still further object is to provide for positioning the bars, billets or slabs in the furnace in such a manner that they are prevented from toppling over and the passage 35 of heat between adjacent bars, billets or slabs is facilitated.

The present application is a division of my application, Serial No. 420,593, Patent 35 No. 1,447,588, granted March 6, 1923.

It has heretofore been proposed to heat metal billets by feeding them one behind the other into a furnace to form a division wall between adjacent flues and passing the 40 heating medium in the same direction through the flues above and below the billets. Such furnaces are generally known as the "split flame" type.

45 By the present invention the heating medium is passed over one side of the billets in one direction and then over the other side of the billets in the opposite direction. Furthermore, the billets are preferably spaced to permit the passage of a portion 50 of the heating medium between adjacent billets.

This method of heating is of great advantage as compared with the "split flame"

method. In actual practice it is impossible to make half of the flame flow above the 55 steel and the other half below—one of the two passages will always be favored. This generally results in non-uniform heat distribution in the billets; a condition which is fatal to accurate rolling or other operations succeeding the heating. To overcome this a soaking hearth has generally been resorted to. That is, the furnace has been made longer than necessary in an attempt 60 to give the billet time to equalize its heat 65 content by conduction.

In the present invention, the heating medium is passed along one side of the billets in one direction and then it is reversed and 70 passed along the other side in the other direction. The surface which first comes in contact with the heating medium will get hotter than the material last touched thereby since there is necessarily a temperature 75 gradient along the path of the heating medium. Therefore, when a billet first enters the furnace it will be heated more on one side than on the other. This is offset to some extent, however, by the spacing of the 80 billets. The pressure drop through the furnace induces the passage of the heating medium between the billets thereby heating them on all sides and tending to equalize the heat content of a billet by conduction more rapidly than would be the case if the billet 85 were heated on two sides only.

It will be noted that the heating medium reverses itself at the delivery end of the furnace so that as the billets travel through the furnace the gases above and below them 90 approach the same temperature and the billets when delivered are uniformly heated. The reversal of flow of all the heating medium does away with the non-uniformity of 95 heating found in the "split flame" type of furnace and also eliminates the large hearth formerly necessary. It will be understood that a soaking hearth may be used to insure the heating of the core of large billets but it need not be so large as has heretofore been 100 necessary.

Referring to the accompanying drawings in which I have shown a preferred method of carrying out my invention, the numeral 105 2 designates the heating chamber of a pair-heating furnace of the continuous type.

The floor or hearth of the heating chamber is provided with a slide-way 3 for the material to be heated, this slide-way being preferably formed by water-cooled skids. 5 The furnace is provided at one end with a heating chamber (not shown) from which the products of combustion pass through the lateral opening 4 into the heating chamber, above the slide-way. Below the floor or hearth, the furnace is provided with one or more longitudinal flues 5 for the circulation of the heated products of combustion in a reverse direction, this flue or flues communicating at the delivery end of the furnace with the heating chamber above the slideway through a suitable opening or openings 6. A particular furnace which I prefer to employ is more fully shown and described in my said application Serial No. 10 420,593, Patent No. 1,447,588.

7 designates any suitable pusher device for pushing the bars, billets or slabs A to be heated, into and through the heating chamber 2, this pusher being formed with a sloping face 8 for maintaining the bars, etc., in an inclined position, as shown. 9 designates any suitable door, and 10 any suitable actuating mechanism therefor, this door closing the entrance opening 11 into the heating chamber. 12 designates a retaining device, which is shown as being in the form of a hooked arm pivoted at 13 and adapted to fall by gravity into engagement with the outermost bar or slab and hold the same at the inclination given it by the pusher 7. The lower face of this hooked arm is beveled so that as the bars or slabs are pushed thereunder by action of the pusher, the arm will readily move upwardly and permit the passage thereof. Immediately thereafter, the arm will drop downwardly to catch the last bar or slab in the manner clearly shown in Figures 1 and 2, thus maintaining the entire series thereof in inclined positions. The bars or slabs being set on edge in this manner, their inclination prevents the leading bars or slabs from toppling over, and insures their passage through the furnaces in such inclined positions.

It will also be noted that the flue or flues 5 are open at the top, the bars or billets forming in effect the top wall of such flue or flues, and a division wall between the said flue or flues and the heating space above the bars or billets. In this manner the heated products of combustion are first caused to pass longitudinally above the bars or billets and thence backwardly in contact with the lower edges of the same, thus giving, a very effective and uniform heating action, as well as utilizing considerable heat which would otherwise be passed to the stack and be lost.

65 By reference to Figures 2 and 3, it will

be noted that the burrs 14 which are formed during the shearing operation are utilized for separating or spacing adjacent bars or billets so as to provide narrow passages 15 between them, these passages permitting the direct passage of a portion of the products of combustion from the heating chamber into the flue or flues 5. It has been found that by reason of the relatively small area of these passages, oxidation of the flat surfaces of the material is prevented, and that due to the more intimate contact with the heated products of combustion, the period necessary for proper heat penetration and uniform heating may be considerably reduced. The passage of the products of combustion directly between the adjacent bars or slabs is facilitated by the use of the open top flue or flues 5, so that the material itself forms the division wall between opposite moving currents of the heating medium.

In operation, heating gases enter the furnace through the opening 4 and move toward the right, as viewed in Figure 1 above the billets and as indicated by arrows. As they move in this direction a certain portion of the gases passes between the billets on account of the openings provided by the burrs thereon, while the remainder of the heating gases travel to the right hand end of the furnace, then downwardly and to the left underneath the billets. The gases which find their way between the billets also pass into this flue 5 from which all the gases travel to the stack, as indicated by the dotted arrow. The heated billets are removed in any convenient manner at the right hand end of the furnace, the leading billet of the advancing line being preferably removed and the remaining line moved forward.

While I have illustrated one manner of carrying out my invention it will be understood that I am not limited to the form shown as the invention may be otherwise embodied within the scope of the following claims.

I claim:

1. The method of heating billets, comprising charging the billets into a heating furnace, and supporting said billets from the charging end of the furnace to maintain them similarly inclined within the furnace, and to prevent toppling thereof, substantially as described.

2. The method of heating sheet bars, comprising feeding the sheet bars broad side into a heating furnace, maintaining the sheet bars within the furnace so disposed with respect to the horizontal that the sheet bars, unless supported would topple, and supporting the sheet bars against toppling.

3. The method of heating sheet bars, comprising feeding the sheet bars inclined to the horizontal into a heating furnace, main-

taining the sheet bars within the furnace and substantially similarly inclined transversely of the furnace, and supporting the sheet bars against toppling during their 5 broad side travel through the furnace.

4. The method of heating billets, comprising feeding said billets into a heating furnace, causing said billets to form a division wall between adjacent flues, and passing a heating medium through said flues, said billets being held in spaced relation by the burrs formed thereon during shearing, substantially as described.

5. The method of heating billets, comprising feeding said billets into a heating furnace while maintaining them in an inclined position, causing said billets to form a division wall between adjacent flues, and passing a heating medium through said flues, substantially as described.

6. The method of heating billets, comprising feeding said billets into a heating furnace, causing said billets to form a division wall between adjacent flues, and passing a heating medium in succession first through one of said flues in one direction on one side of the billets, for substantially the entire length of the charge of billets in the furnace, then to the opposite side of said billets to another of said flues, and then through said last mentioned flue in a direction opposite to the direction of travel through the first mentioned flue, for substantially the entire length of the charge of billets in the furnace, substantially as described.

7. The method of heating billets, comprising feeding said billets into a heating furnace, causing said billets to form a division wall between adjacent flues, and passing a heating medium in succession first through one of said flues in one direction on one side of the billets, then to the opposite side of said billets to another of said flues, and then through said last mentioned flue in a direction opposite to the direction of travel through the first mentioned flue, the heating medium being introduced to and taken from the flues adjacent the same end of the furnace for substantially the entire length of the charge of billets in the furnace, substantially as described.

8. The method of heating billets, comprising feeding said billets into a heating furnace, causing said billets to form a division wall between adjacent flues, and introducing a heating medium into said furnace and causing it to initially travel through one of said flues in the direction of travel of the billets through the furnace, the heating medium being introduced to and taken from the flues adjacent the same end of the furnace, substantially as described.

9. The method of heating billets, comprising feeding said billets into a heating furnace, causing said billets to form a division

wall between adjacent flues, introducing a heating medium into said furnace, causing said medium to initially travel through one of said flues in the direction of the travel of the billets through the furnace, and then causing said medium to pass to the opposite side of said billets and travel through another of said flues in a direction opposite to its direction of travel through said first mentioned flue, the heating medium being introduced to and taken from the flues adjacent the same end of the furnace, substantially as described.

10. The method of heating billets which includes feeding billets into a heating furnace, passing a heating medium through the furnace over one side of the billets, and then changing its direction and passing it back through the furnace over the other side of the billets, meanwhile allowing a portion of the heating medium to pass between the billets, and removing the billets from the furnace adjacent the end where the direction of travel of the heating medium is changed, the heating medium being introduced to and taken from the flues adjacent the other end of the furnace, substantially as described.

11. The method of heating billets which includes feeding billets in a row into a heating furnace, passing a heating medium through the furnace over one side of the billets, passing it around the foremost billet and back over the other side of the billets, meanwhile allowing a portion of the heating medium to pass between the billets, removing the foremost billet and advancing the remaining billets by inserting a cold billet at the other end of the row, the heating medium being introduced to and taken from the flues adjacent the end of the furnace where the cold billets are introduced, substantially as described.

12. The method of heating billets which includes feeding billets in a row into a heating furnace, passing a heating medium through the furnace over one side of the billets, passing it around the foremost billet and back over the other side of the billets, removing the foremost billet and advancing the remaining billets by inserting a cold billet at the other end of the row, the heating medium being introduced to and taken from the flues adjacent the end of the furnace where the cold billets are introduced, substantially as described.

13. The method of heating billets which includes passing a heating medium first over one side of a row of billets in one direction and then over the opposite side of the billets and in the opposite direction, meanwhile allowing a portion of the heating medium to pass between the billets, substantially as described.

14. The method of heating billets which includes passing a heating medium in a di-

rect manner first over one side of a row of spaced billets in one direction and then over the opposite side of the billets and in the opposite direction, substantially as described.

15. The method of heating billets which includes supplying a gaseous heating medium to one side of a row of spaced billets, passing portions of the medium between different billets of the row at different points along the length of the row, the gases being first passed along the side of the row where the gases enter a sufficient distance to reach the points where the various portions pass between the billets and then in a reverse direction along the side of the billets opposite the side first in contact with the heating medium, substantially as described.
16. The method of heating billets which includes supplying a heating medium to one side of a row of spaced billets, passing portions of the medium between different billets of the row at different points along the length of the row, the gases being first passed along the side of the row where the gases enter a sufficient distance to reach the points where the various portions pass between the billets and then in a reverse direction along the side of the billets opposite the side first in contact with the heating medium and providing an excess of heating medium above the quantity passing between the billets, said excess passing over that side of the row first in contact with the heating medium, reversing its direction at the end of the row of billets and passing through the opposite side, substantially as described.

17. The method of heating billets, comprising feeding the billets into a heating furnace, and maintaining a plurality of said billets inclined in the same direction and supported substantially along one corner only thereof by the furnace and in a common plane within the furnace, substantially as described.

18. The method of heating billets, comprising feeding the billets broad side into a heating furnace, maintaining a plurality of said billets within and transversely of the furnace and inclined in the same direction therein with the center of gravity of the billets so disposed that a side support therefor is required to prevent toppling thereof, and providing a side support for the billets, substantially as described.

19. The method of heating sheet bars, comprising supporting the bars on edge with the edges in a common plane and the bars in adjacent relationship and in an inclined position, feeding the bars broad side while so inclined and so supported into a heating furnace, and maintaining the bars in inclined position within said furnace, substantially as described.

20. The method of heating bars, comprising

placing the bars in side by side inclined relationship outside of the furnace and extending transversely thereof, feeding the bars broad side into a furnace while so inclined, and maintaining the bars in inclined position within the furnace, substantially as described.

21. The method of charging sheet bars, comprising feeding the bars broad side while supported on edge through a charging opening and into a heating furnace, and engaging the rearmost bar of each charge at a point adjacent the charging opening of the furnace to prevent toppling.

22. A method of heating bars, comprising feeding the bars broad side into a furnace with the lower edges of adjacent bars resting on a common support in substantially a common plane, and maintaining a plurality of the bars inclined relatively to said support in said furnace, substantially as described.

23. In the method of heating relatively thin metal shapes, the steps comprising charging broad side a plurality of such shapes supported edgewise into a furnace, maintaining at least a plurality of such shapes within the furnace backwardly inclined to the horizontal and toward the charging opening sufficiently to dispose the center of gravity of each of such billets in a position to cause rearward toppling thereof, and supporting the billets against rearward toppling, substantially as described.

24. In the method of heating relatively thin metal shapes, the steps comprising charging a row of such shapes broad side into furnace, maintaining at least the major part of the shapes in such row within the furnace backwardly inclined to the horizontal and toward the charging opening sufficiently to prevent forward toppling of such portion, charging fresh shapes into supporting relation to those within the furnace, and engaging said freshly charged shapes adjacent the charging end of the furnace to prevent rearward toppling, substantially as described.

25. In the method of heating relatively thin metal shapes, the steps comprising charging a row of such shapes broad side into a furnace, maintaining at least the major part of the shapes in such row within the furnace backwardly inclined to the horizontal and toward the charging opening sufficiently to prevent forward toppling of such portion, and charging fresh similarly inclined shapes into supporting relation to those within the furnace, substantially as described.

26. In the method of heating relatively thin metal shapes, the steps comprising charging a row of such shapes supported cornerwise into a furnace, and maintaining the shapes of the major part of said row

inclined sufficiently to the horizontal and backwardly toward the charging opening to prevent forward toppling thereof. 40

27. In the method of heating relatively thin metal sections, the steps comprising charging a row of such sections supported edgewise into a furnace, and maintaining the shapes of the major part of said row backwardly inclined to the horizontal and toward the charging opening sufficiently to prevent forward toppling by supporting the row from the charging end of the furnace. 50

28. In the method of heating relatively thin metal shapes, the steps comprising charging a row of such shapes into a furnace, and supporting the shapes from the charging end of the furnace so as to maintain the shapes of the major part of the row backwardly inclined to the horizontal sufficiently to prevent forward toppling thereof. 55

29. The method of charging sheet bars, comprising feeding the bars broad side while supported on edge into and through a heating furnace to provide a substantially continuous row of sheet bars within said furnace, and engaging an end bar of the row to prevent toppling thereof. 60

30. In the method of heating relatively thin metal sections, the steps comprising charging the sections into a furnace, and supporting the same from the charging end of the furnace in such manner as to prevent toppling thereof, charging fresh sections into the furnace to advance and support the previously charged sections, and similarly supporting the freshly charged sec- 65

tions from the charging end of the furnace, substantially as described. 70

31. In the method of heating relatively thin metal shapes, the steps comprising charging a row of shapes into the furnace, supporting the freshly charged shapes from the charging end of the furnace backwardly inclined to the horizontal, and utilizing the charged shapes to maintain the shapes of the greater part of the row similarly inclined, substantially as described. 75

32. In the method of heating relatively thin metal shapes, the steps comprising moving shapes supported broad side to broad side along skids, and so maintaining the same on the skids that they are prevented by gravity from forward toppling by maintaining the center of gravity of such shapes in such position as to effect rearward toppling, and holding such shapes against rearward toppling, substantially as described. 80

33. In the method of heating relatively thin metal shapes, the steps comprising charging a plurality of such shapes into a furnace with one of their broad faces toward the charging opening of the furnace, maintaining at least a plurality of such shapes within the furnace inclined to the horizontal sufficiently to dispose the center of gravity of such shapes offset with respect to the supporting edge thereof sufficiently to produce toppling, supporting the shapes against such toppling, and charging fresh shapes into the furnace and into engagement with the previously charged shapes. 85

In testimony whereof I have hereunto set my hand.

THOMAS J. COSTELLO.
